UNITED STATES PATENT OFFICE

CHARLES W. KIRSCH AND ARCHIE A. ALLEN, OF STURGIS, MICHIGAN, ASSIGNEES TO
KIRSCH COMPANY, OF STURGIS, MICHIGAN, A CORPORATION OF MICHIGAN

MACHINE FOR IMPRESSING HELICALLY-DISPOSED FORMATIONS IN CURTAIN POLES

Application filed June 17, 1929. Serial No. 371,431.

This invention relates to machines for shaping and ornamenting wood curtain poles by means of the application of heat and pressure to the surfaces thereof, the structure illustrated in the accompanying drawings and hereinafter described being intended and adapted for shaping or ornamenting the poles helically throughout the length of the latter.

The main object of the present invention is to provide simple, durable and efficient machines adapted for the above named purposes.

In the accompanying drawings, illustrating the invention in a suitable embodiment thereof:

Fig. 1 is a top plan view of a machine of the kind specified embodying the invention.

Fig. 2 is an end elevation of the same.

Fig. 3 is a central longitudinal section of the same on the line 3—3 of Fig. 1.

Fig. 4 is a plan section of the same on the line 4—4 of Fig. 3.

Fig. 5 is a detail vertical section of the same on the line 5—5 of Fig. 1.

Fig. 6 is a detail view in elevation of an adjustable bearing support and bearing for one of the main shafts of the machine.

Fig. 7 is a section of the same on the line 7—7 of Fig. 6.

Fig. 8 is a fragmentary detail section on the line 8—8 of Fig. 2.

Fig. 9 is an inverted detail plan section on the line 9—9 of Fig. 8.

The machine comprises a suitable supporting frame which includes the table plate 1 substantially centrally of which there is an opening or bearing for the lower end of a vertical shaft 2 on which the worm-wheel 3 is splined. The main bearing 4 for the shaft 2 is mounted on the table plate 5 disposed above and parallel with the plate 1.

Suspended from the plate 5 are the bearings 6 and 7 for the main shaft 8 of the machine, which carries a worm meshing with the worm-wheel 3 and a spur-gear 9 meshing with a spur-pinion 10 on the shaft of an electric motor or other power source 11. The said worm is not specifically illustrated as unnecessary.

Mounted upon the upper end of the shaft 2 is a bevel gear 12 which meshes with the bevel pinions 13 and 14 of counter shafts 15 and 16, respectively, which extend angularly of each other and substantially diagonally of the plates 1 and 5 in horizontal planes parallel with said plates. The shafts 15 and 16 are journaled in sleeve bearings 17 suitably equipped with bushings and which are supported upon brackets 18 and 19, respectively, of plates 20 and 21 resting upon the plate 5 and having overlapping middle portions pivotally engaged with the shaft 2 to permit adjustment of said plates arcuately about the axis of said shaft for reasons which will hereinafter fully appear. The plates 20 and 21 will be hereinafter referred to as "scissors plates".

On the shaft 15 there is mounted a spur pinion 22 which meshes with the internal spur-gear 23 mounted on a shaft 24 journaled at one end portion in the bearing 25 carried by the bracket 18 and at its other end portion in a bearing 26 carried by the vertically adjustable support 27 of the bracket 28 integral with the scissors plate 20.

The shaft 16 carries the spur-pinion 29 which meshes with an idle spur-gear 30 on a stud shaft 31 carried by the bracket 19 and meshing with the spur-gear 32 on the shaft 33 which is journaled at one end in a bearing 34 carried by the bracket 19 and at its other end in a bearing 35 carried by the adjustable support 36 of the bracket 37 integral with the scissors plate 21.

Mounted upon said plate 5 are the supports 38 and 39 for guide sleeves 40 through which a pole 44 to be subjected to the action of the mechanism is passed, the diameters of said sleeves 40 being such as to accord substantially with that of the pole, the instant mechanism being adapted for the treatment or shaping of normally cylindrical poles only to impart to them the shape of heavy rope.

The shafts 24 and 33 are disposed, respectively below and above the guide sleeves 40 for the pole and angularly to the axis of the latter. Said shafts rotate at equal speed in the same direction, i. e. clockwise, and each thereof carries a roller 41 and 42, respectively,

which, in the instance illustrated, are provided with parallel annular ridges 43 bordered by rounded surface formations, the ridges 43 being adapted to impress helical grooves in the pole 44 and rotate the latter as the shafts 24 and 33 are rotated and, by reason of the continuity of the helical grooves, also serve to impart longitudinal movement to the pole.

In the instant case, the rollers 41 and 42 shape the pole 44 by the exercise of pressure only but, obviously, if desired, the said rollers may be suitably maintained hot by gas jets impinging thereon to thus burn the grooves into the pole. In instances where other ornamentation or ornamental effect is to be imparted to the pole, the surface formation of the rollers 41 and 42 may be other than the ridges 43 as will be obvious, it being also obvious that the said rollers may include other ornamenting means with the said ridges.

As shown in Figs. 5 to 7, inclusive, the bearings for the shafts 24 and 33 are vertically adjustable to thereby regulate or determine the pressure exerted by the rollers 41 and 42 on the pole 44 and to balance the pressures exerted by said rollers upon diametrically opposite portions of said pole.

It will be noted by reference to Fig. 5 that the bearings 25, 26, and 34, 35 are secured to the uprights of the brackets 18, 19 and 28, 37 by means of set-screws or machine bolts 45, 46, respectively, which pass through vertical slots 47, 48, respectively in said brackets.

Figs. 8 and 9 illustrate the means employed to adjust the position of the idle gear 30 to accord with variations in adjustment of the shaft 33. The stud shaft 31 has a threaded shank portion receiving the nut 49 and, at its other end has a head 50 provided with recesses 51 presenting parallel side faces engaging the side walls of a slot 52 in the plate 53 which is mounted on a bracket 54 secured to the bracket 19 and vertically adjustable on the latter, thus permitting said idler to be moved both vertically and horizontally into proper mesh with the pinion 29 and gear 32.

The arms 20 and 21 carrying the brackets 18, 19 and 28, 37 ordinarily will require only very negligible arcuate adjustment to bring the ridges of the rollers 41 and 42 into such proper relative positions as to cooperate to produce the grooves in the pole at any desired pitch. Such arcuate adjustment is permitted by providing arcuate slots 56 in the plate 5 through which the shanks of the bolts 57, for clamping the plates 20 and 21 against movement, project.

The relative arrangement of the shafts 24 and 33, the bearings therefor and the rollers thereon is such that planes intersecting the respective rollers 41 and 42 midway between the pairs of annular ridges thereof, intersect

each other in the axis of the vertical shaft 2. The axis of the latter intersects the axis of the guide sleeves 40. This relative arrangement permits the pitch of the helical grooves of the pole 44 to be varied by varying the angle of intersection of the vertical planes of the axes of the shafts 24 and 33 with respect to each other and equally with respect to the vertical plane of the axis of the sleeves 40.

Obviously the helical grooves of the pole 44 are in the nature of a multiple thread of a very long pitch.

In practice, it is essential that the bearings for the shafts 24 and 33, respectively, be so adjusted in relative elevation that the horizontal planes of their axes are equidistant from the axis of the guide sleeves 40 for the pole 44 so that the rollers 41 and 42 will exert equal pressures on diametrically opposite sides of the said pole.

It will be noted that because of longitudinal movement imparted to the pole 44 by the rollers 41 and 42, there will be a tendency of the shafts 24 and 33 to move longitudinally in the opposite direction and that this thrust movement must be prevented in order to maintain the rollers 41 and 42 properly positioned relatively to each other and to the axes of the shaft 2 and sleeves 40, respectively. To this end the said shafts 24 and 33 are provided with collars 58 and 59, respectively, engaging the end faces of the bushings of bearings 25 and 34.

In operation, after proper adjustment of the shafts and impressing rolls, poles are successively fed by hand to said rolls through one of the guide sleeves and forced into initial engagement with said rolls which thereupon impart both rotary and longitudinal movement to feed the pole into the other of said guide sleeves where it remains after passing out of engagement with the said rolls, the next succeeding pole serving to eject the same.

We claim as our invention:

1. A machine for forming curtain poles comprising a guide for the pole permitting longitudinal and rotary movement thereof, a pair of shafts arranged angularly to each other and to the longitudinal axis of said guide, impressing rolls mounted on said shafts and arranged to engage a pole at diametrically opposite points in the surface of the latter, a drive shaft, and gearing between the latter and said shafts for rotating the latter simultaneously in one direction at equal speed to thereby impart longitudinal and rotary movement to the pole.

2. A machine of the kind specified including a pair of shafts spaced from each other and extending angularly to each other, a pair of pole impressing rolls mounted on said shafts, guides for a pole permitting longitudinal and rotary movement of the latter be-

tween said rolls arranged with the longitudinal axis of said guides extending at equal angles to the longitudinal axes of said shafts, the said rolls adapted to engage a pole carried in said guides at diametrically opposite sides, bearings for said shafts adjustable to cause said rolls to bear equally on a pole, a drive shaft, and gearing between the drive shaft and said first-named shafts for rotating the latter in one direction at equal speed to thereby impart longitudinal and rotary motion to the pole while impressing the same.

3. A machine of the kind specified comprising a support, a vertical shaft mounted in bearings on said support, a pair of plates pivotally mounted on said support on the pivotal axis of said shaft at their middle portions, pairs of bearings for a pair of shafts mounted upon the respective plates at opposite ends thereof, a pair of shafts journalled in said respective pairs of bearings, said shafts extending angularly to each other and having their axes intersecting in the axis of the vertical shaft, a pair of pole impressing rolls mounted on said shafts at said point of intersection of their axes, a pair of guides rigidly mounted on said support with their common longitudinal axis intersecting the axis of said vertical shaft and extending at equal angles to the axes of said pair of shafts and equidistantly from the latter, said impressing rolls adapted to engage a pole carried in said guides at diametrically opposite points and impart longitudinal and rotary movement to said pole as said pair of shafts is rotated, means for rotating said vertical shaft, and gearing between the latter and said pair of shafts for rotating both the latter in one direction at equal speed.

4. A machine of the kind specified including a support, a vertical shaft journalled in bearings thereon, a pair of crossed plates pivoted at their overlapped portions on said shaft, pairs of bearings mounted at the end portions of said plates, a pair of crossed shafts journalled in said bearings and spaced from each other, pole impressing rollers mounted on said shafts in alignment with the axis of said vertical shaft, pole guides disposed to support a pole in position axially intersecting the axis of said vertical shaft and at equal angles to the axis of said pair of shafts and for engagement by said rolls at diametrically opposite sides, a bevel gear on said vertical shaft, counter-shafts journalled in bearings on said plates and equipped with bevel pinions meshing with said bevel gear, spur-pinions at the other ends of said counter-shafts, an internal gear on one of said first-named shafts meshing with one of said spur-pinions, and a gear train associating the other of said first-named shafts with the spur-pinion of the

other counter-shaft, said plates being arcuately adjustable.

5. A machine of the kind specified comprising a support, a pair of crossed-plates pivotally mounted at their overlapped middle portions on said support and arcuately adjustable relatively to each other, shafts journalled in bearings on said respective plates and crossing each other at a point in alignment with the pivot of said plates, rollers mounted on said shafts and equipped with pole impressing formations intersected by the said pivotal axis of said plates, pole guiding and supporting means arranged to support a pole with its axis intersecting said pivoted axis and extending at equal angles to the axis of said shafts and between said rollers for engagement by the latter at diametrically opposite sides.

6. A machine of the kind specified including pole guides for supporting a pole and permitting longitudinal and rotary movement thereof, a pair of impressing rolls arranged for engaging the pole at diametrically opposite points, said rolls rotatable on axes extending substantially transversely of each other and at equal angles to the axis of the pole, a source of power, and gearing between the latter and said rolls for rotating the same at equal speed in one direction.

7. A machine of the kind specified including pole guides for supporting a pole and permitting longitudinal and rotary movement thereof, a pair of impressing rolls arranged for engaging the pole at diametrically opposite points, said rolls rotatable on axes extending substantially transversely of each other and at equal angles to the axis of the pole, means for adjusting said rolls to bear with equal force on an interposed pole, a source of power, and gearing between the latter and said rolls for rotating the same at equal speed in one direction.

8. A machine of the kind specified including pole guides for supporting a pole and permitting longitudinal and rotary movement thereof, a pair of impressing rolls arranged for engaging the pole at diametrically opposite points, said rolls rotatable on axes extending substantially transversely of each other and equal angles to the axis of the pole, means for adjusting said rolls to bear with equal force on an interposed pole, means for adjusting the angular position of said rolls relatively to each other and the pole axis, a source of power, and gearing between the latter and said rolls for rotating the same at equal speed in one direction.

9. A machine of the kind specified including pole guides for supporting a pole and permitting longitudinal and rotary movement thereof, a pair of impressing rolls arranged for engaging the pole at diametrically opposite points, said rolls rotatable on axes extending substantially transversely of each

- other and equal angles to the axis of the pole, means for adjusting said rolls to bear with equal force on an interposed pole, means for adjusting the angular position of said rolls relatively to each other and the pole axis, a vertical shaft common to both said rolls, gear-trains associating the respective rolls with said vertical shaft and adjustable with said rolls, and a source of power geared to said vertical shaft.
10. A machine of the kind specified including a support, a table-plate thereon, a vertical shaft projecting through said plate, a pair of scissors plates pivoted at their middle portions to said table plate concentrically with said vertical shaft, brackets at the outer ends of said scissors plates, bearings vertically adjustable on said brackets, a pair of crossed shafts journalled in said adjustable bearings and spaced from each other, non-adjustable counter-shafts journalled in bearings on said scissors plates, gearing associating said countershafts with said first-named shafts and said vertical shaft, a pole guide arranged to support and permit longitudinal and rotary movement of a pole and axially positioning the latter with respect to the axis of the vertical and the crossed-shafts, and pole impressing rolls mounted on the latter for engagement with diametrically opposite points of the pole intersected by the axis of the vertical shaft.

In testimony whereof, we have hereunto set our hands this 5th day of June, 1929.

CHARLES W. KIRSCH.
ARCHIE A. ALLEN.
